UNITED STATES PATENT OFFICE.

CARL J. PETERSON, OF PROVO, UTAH.

ROTARY PUMP.

Application filed February 16, 1925. Serial No. 9,561.

To all whom it may concern:

Be it known that I, CARL J. PETERSON, a citizen of the United States, residing at Provo, in the county of Utah and State of Utah, have invented certain new and useful Improvements in Rotary Pumps, of which the following is a specification:

My invention relates to pumps and has for its object to provide a compact rotary ball-valve pump wherein centrifugal action, and a water pressure in the discharge pipe, act on the balls to hold them in the water passage of the pump.

These objects I accomplish with the device illustrated in the accompanying drawings in which similar letters and numerals of reference indicate like parts throughout the several views and as described in the specification forming a part of this application and pointed out in the appended claims.

In the drawings in which I have shown the best and most substantial embodiment of my invention, Figure 1 is a side elevation of the pump showing the suction and discharge inlets. Figure 2 is an edge elevation of the pump looking in the direction of the intake port. Figure 3 is a vertical section on line 3-3 of Figure 2. Figure 4 is a vertical section on line 4-4 of Figure 1. Figure 5 is a side elevation of the ball-carrying impeller. Figure 6 is an edge elevation of the impeller and a portion of its shaft. Figure 7 is a plan view of one side of the ball case showing the ball race therein. Figure 8 is an edge view of the same.

My invention consists of a casing A having an open interior and provided with a closure plate B on one side thereof; said casing is provided with a threaded inlet opening C and a threaded outlet opening D. A bearing boss *a* is integrally formed on the said casing A and a like boss *b* on the closure plate B. The said casing A is eccentrically bored through its side wall with the bore extending through its boss *a*, and the said closure plate B is eccentrically bored in alinement with the bore in the said casing A, and with the bore extended part way through the boss *b* to form a bushing chamber *e*, which is bushed with graphite or other suitable bushings, as at *c*, to form a bearing for the shaft E of the pump. Connected with the interior of the discharge opening D of the pump is a pipe 1 which enters the bearing chamber *e* of the device and connects with an axial longitudinal conduit 2, bored

in the end of the shaft E, through which liquid may pass from the discharge pipe D to the interior of an impeller F. A lubricating pipe 3 is inserted in the discharge opening D and connects the interior of said opening with the shaft E for lubricating the said shaft E in its bearing. The interior of said case A is bored out to form an annular ball casing recess 4, and a portion of the closure plate B is similarly recessed to form the opposed annular recess 5 for the other side of the ball casing. The ball-carrying impeller is mounted on said shaft E and secured thereto to position the said impeller F concentrically within the said recesses 4 and 5, and the periphery of said impeller F is radially bored to receive the balls G. In the drawings shown, four of said bores 6 are provided in said impeller F for the four balls used, and each bore is enlarged by a smaller bore 7. Within said annular recesses 4 and 5 are carried the respective ball cases H and eccentric in position as to said shaft E and impeller F. Each of said ball cases H has portions cut from its periphery to form an opening for the intake, as shown at 8, and one for the discharge of the liquid to the interior of the pump, as at 9, and the interior of the said case A is internally cut away contiguous said openings 8 and 9 to form the intake and discharge chambers of the pump, as shown at J and K. The said impeller F is also radially bored, as shown at M, from the bottom of each of said ball openings 6 to the shaft opening *e* in which shaft E is operated, and within each of said chambers M is carried a cylindrically-shaped plunger cup 16, and said chambers M are in open connection with the bore 2 in the end of the shaft E in order that liquid may be held under the pressure of the water head in the discharge opening D in the pipe 1, opening 2, and each of said chambers M to keep the said plunger cups 16 constantly bearing against the balls G, which pressure, when combined with the centrifugal force of the rapidly moving impeller and balls, will force the balls into and hold them as valves in the crescent-shaped eccentric opening 15 formed between the impeller F and said cases H. To insure a proper setting of the ball cases H in the casing A, I provide a position pin 14 in the meeting line between said casing A and cases H. A packing gland P is provided around said shaft E for sealing any possible leak from the interior of said casing.

The operation of my pump is as follows: With power applied to rapidly rotate the shaft E, the balls G will be, by centrifugal force, held to their outer position in said ball cases H and water will be drawn through the inlet C and carried in the excentric space 15 between said cases H and the periphery of the impeller from opening J to opening K and be forced through the discharge opening. The pressure of the water through the pipe 1 and bore 2 will force the plunger cups 16 outwardly in their respective radially-disposed chambers M and prevent the balls from falling by gravity away from the inner wall of the cases H; and said balls will force the water between the cases and the periphery of the impeller F through the discharge opening.

Having thus described my invention, I 20 desire to secure by Letters Patent and claim:—

1. A rotary pump comprising a casing having an inlet and an outlet opening, both of which connect with the interior of said casing a shaft bore provided in the end walls of said casing; a packing carried in said bore; a shaft journalled in said packing, one end of which is spaced from the end of said bore and centrally bored and on which a ball carrying impeller is secured; a pipe connecting the discharge opening of said casing with the central bore of said shaft; radially disposed ports from the said central bore to the periphery of said shaft; a ball-carrying impeller mounted excentrically in the interior of said casing; a plurality of balls carried in said impeller; radially disposed central bores through said impeller; plunger cups carried in said radial bores by which 40 said balls are supported and adapted to be moved outwardly when the water is dis-

charged through the discharge pipe connected with the outlet opening of said casing.

2. A rotary pump comprising a hollowed out casing having an inlet and an outlet opening connected with the interior of said casing; a ball race carried within said casing and having elongated slots in its periphery in open connection with the respective openings in said casing; a ball-carrying impeller excentrically mounted in said casing and ball race and having radially disposed openings therein; a ball carried in each of said impeller openings and operable within said race; and a rotatable shaft journalled in said casing and on which said impeller is secured.

3. A rotary pump comprising a hollowed out casing having an intake and an outlet opening, both of which are connected with the interior of said casing; a ball housing concentrically secured in said casing and having elongated slots opening through its periphery contiguous the respective intake and outlet openings of said casing; a ball-carrying impeller excentrically mounted for rotation in said ball housing and having radially disposed holes of different sizes bored therein; a ball carried in each of the larger sizes of said holes; cylindrical cup 70 plungers carried in each of the smaller sized holes and adapted to bear against the balls adjacent; a rotatable shaft journalled in said casing having an axial bore therein and radially connected with the holes in said impeller; and a conduit connecting the outlet opening of said casing with the axial bore of said shaft.

In testimony whereof I have affixed my signature.

CARL J. PETERSON.
